MAGNETIC TAPE TRANSPORT

Ronald E. Loosen, Woodland Hills, and Leon C. Sanderson, Los Angeles, Calif., assignors to Ampex Corporation, Redwood City, Calif., a corporation of California

Filed Nov. 9, 1964, Ser. No. 82,522

Term of patent 14 years

(Cl. D26—5)

FIG. 1

Des. 204,938

PAGE 2

FIG. 2

FIGURE 1 is a front and right side perspective of a magnetic tape transport, showing our new design; FIGURE 2 is a back and left side perspective; and

FIGURE 3 is a left side elevation.

The dominant features of our new design are shown in solid lines in the drawing. The tape reels are shown in broken lines for illustrative purposes only.

The dominant features of the design reside in the use of front, rear and side panels of substantial thickness meeting in re-entrant corners and terminating short of the top and bottom of the cabinet to define a crowned top and a bottom overhang; a transparent front window, bent back at the sides and surmounted by a marquee to substantially conform to the envelope of the front panel; an opaque horizontal mask behind the lower portion of the window and following the bends thereof; and a horizontal row of controls mounted above the marquee and offset to one side.

We claim:

The ornamental design for a magnetic tape transport, substantially as shown and described.
